UNITED STATES PATENT OFFICE.

ALFRED T. KRUSE, OF DEFIANCE, OHIO, ASSIGNOR, BY MESNE ASSIGNMENTS, TO THE AMERICAN STEEL PACKAGE COMPANY, OF DEFIANCE, OHIO, A CORPORATION OF OHIO.

SHEET-METAL PACKING-CASE.

No. 870,728.

Specification of Letters Patent.

Patented Nov. 12, 1907.

Application filed February 4, 1904. Serial No. 192,058.

To all whom it may concern:

Be it known that I, ALFRED T. KRUSE, a citizen of the United States, residing at Defiance, in the county of Defiance and State of Ohio, have invented certain 5 new and useful Improvements in Sheet-Metal Packing-Cases, of which the following is a specification.

My invention relates to improvements in sheet-metal packing-cases, especially designed for the transportation and storage of liquids, such as mineral waters, 10 milk, beer, pop etc. contained in bottles and similar vessels.

This packing-case is admirably adapted to the transportation and storage of bottled beer consisting of a rectangular case having its walls made up of sheet-metal of 15 such form as to give it proper strength, and provided with a perforated bottom, and a hinged lid or cover, of strong construction, adapted to fit down within and flush with the top edges of the sides and ends of the case thus adding to the strength of the same, and provided 20 with a hasp and lock by means of which the contents of the case may be securely locked therein.

The bottles are mounted and supported in the case in their proper upright position by means of two supporting-plates mounted and interposed between the 25 ends and sides of the case, thereby greatly stiffening and strengthening the same, and provided with a series of openings adapted to receive and support the bodies of the bottles.

Holders for bottles etc. have been extensively employed for the carrying of liquids from place to place, and said holders have usually been made of wooden boxes with partitions or divisions to prevent the bottles coming into direct contact with each other, and, in some instances, a false bottom has been employed, 30 with perforations adapted to receive the bottle necks. Such holders, however, are objectionable from the fact that, being made of wood, they soon become soaked with fluid, filthy, decayed, and broken.

The paramount object of the present invention is to 40 produce a generally improved sheet-metal packing-case better suited to its intended purposes than any other device of the same class with which I am acquainted, and which, by reason of the particular construction of the metal, and its general construction, 45 will render the same more durable; and which will be more cleanly and take up less space in transportation and storage than the holders heretofore constructed out of wood.

With these ends in view the invention consists in the 50 novel construction, arrangement and combination of parts hereinafter described, illustrated in the accompanying drawings, and particularly pointed out in the appended claims.

Referring to the drawings, forming a part of this specification, Figure 1, is a side elevation of the improved

case. Fig. 2, is a top plan view of the same, with the lid or cover opened. Fig. 3, is a vertical sectional view. Fig. 4, is a detail view of a blank form of one of the sides, before being crimped and bent into proper form as shown in the other figures of the drawings. 60

Similar numerals of reference indicate like parts throughout all the figures of the drawings.

The case is preferably rectangular, and I have shown, in the present instance, a case constructed of a size large enough to hold two dozen bottles; but the size 65 may be varied to meet various requirements.

The sides 1, and ends 2, are of sheet-metal, preferably of sheet-steel crimped, at suitable distances to form outwardly-extending ribs or flanges 3, of substantially U-shape in cross-section, as shown, and designed to stiffen and strengthen the said sides and ends of the case to the greatest possible degree commensurate with the general character of the material employed. The sides and ends 1, and 2, are preferably made up of separate sheets of sheet-metal, and, when so 70 constructed, are connected and secured at their sides or ends, in any suitable and convenient manner, to form the corners or angles of the case. Said sides and ends 1, and 2, are preferably connected at their sides or ends by having the meeting or contiguous edges 75 thereof bent over and about to form flanged joints at the corners of the case. At the upper and lower edge of the case there is mounted a heavy stiff wire 4, which is secured and inclosed by having the edges of the sides and ends 1, and 2, bent over and about the same 80 forming a beading 5, which together serve to greatly strengthen the case at these points. By reason of the formation of the outwardly-extending ribs or flanges 3, in said sides and ends, it is necessary, before crimping the metal and attempting to inclose the wire 4, by a 85 beading 5, as shown in Figs. 1, 2, and 3, of the drawings, to first cut along the margin of said sides and ends, opposite where the ribs or flanges 3, are to be formed, a series of recesses 6, as shown in Fig. 4, of a width and depth corresponding, approximately, to 90 the width of the metal crimped into the rib or flange 3, and the circumference of the wire inclosed, respectively. 7, designates the bottom of the case, crimped into a similar series of ribs or flanges, and provided 95 with a series of perforations 8, intermediate said series of ribs or flanges, and which serve to drain the case of any liquid which may come within the same, as in washing, cleansing, etc. The bottom 100 7, is secured to the sides and ends of the case, by having its edges bent over and about the beading 5, to 105 form a second beading 9, (see Fig. 3) still further stiffening and strengthening the case at these points.

It will be seen, and this is the preferable construction, that the outwardly-extending ribs or flanges 3, of the sides 1, of the case abut up against the beading 110

5, or in close proximity thereto, whereby the stiffening function or effect referred to, shall be carried substantially across each sheet laterally, and along each edge, and each shall coöperate with the other in attaining 5 the desired result, and that the same are in alinement with the ribs or flanges of the bottom 7, secured to the sides and ends of the case. In this way the beading 5 is braced and strengthened by the oppositely-disposed ribs or flanges 3, formed in the sides and bottom 10 of the case.

10, designates the lid or cover of the case, crimped into a series of ribs or flanges, and provided at its rear with hinge-straps 11, which take over the wire 4, secured within the top beading 5, of the rear side 1, of 15 the case.

The bottom 7, and the lid or cover 10, of the case are each made up of separate sheets of sheet-metal like that shown in Fig. 4, of the drawings, and then crimped into a series of U-shaped outwardly-extending ribs or 20 flanges as shown in the other figures of the drawings.

At the front portion of the lid or cover 10, there is secured a hinged hasp-strap 12, provided with a slot adapted to take over a stop or stud 13, secured to the front side of the case, and together forming a suitable 25 means of securing and locking the case, by means of any suitable and convenient lock.

14, designates a wire mounted about the edges of the lid or cover 10, and secured and inclosed by having the said edges bent over and about the same forming a 30 beading 15, which together serve to greatly strengthen the lid or cover. Furthermore, it will be seen that said lid or cover 10, when closed, fits down within and between the top edges of the sides and ends of the case formed by the beading 5, and flush within the 35 same, so that the case is doubly strengthened at these points when the lid is closed.

15^a, designates supporting-stops for supporting the lid or cover in its closed position.

16, designates two supporting-plates for the bottles, 40 designed to be interposed between, and secured to, the sides and ends 1, and 2, at suitable distances from the bottom of the case, by means of upwardly-extending flanges 17, formed with the sides and ends of said supporting-plates 16, and connected by rivets, or 45 other suitable means, with the sides and ends of the case. It will thus be seen that these supporting-plates 16, with the upwardly-extending flanges 17, will tend to still further strengthen and stiffen the sides and ends of the case at that portion of the case 50 where it is most to be desired.

The supporting-plates 16, are provided with a series of openings 18, adapted to receive and support the bodies of the bottles in their proper upright position in the case, and, in order to form surrounding walls for 55 the bodies of the bottles, and to still further strengthen the supporting-plates, a series of annular downwardly-extending flanges 19, are formed about the openings 18, as shown most clearly in Fig. 3, of the drawings.

20, designates openings formed in the ends 2, of the 60 case, designed to receive and contain sheet-metal handle plates 21, secured to said ends, and having their upper and lower edges about the opening 20, bent to form a beading 22, which takes over the edges of the opening 20, forming a comfortable and convenient hand-hold 65 in these openings.

It will be observed that by the use of sheet-metal, bent and constructed as shown and described, I am enabled to lessen the weight of the case, and, being entirely of metal, can be cleansed with great facility by being immersed in hot water, and it dries rapidly, and 70 occupies less space than wooden boxes, and is more durable.

The case is, preferably, constructed of full cold roll steel and coated by an electrolytic zincing process, making it absolutely non-corrosive. 75

The supporting-plates herein shown and described, but not claimed, are included in the subject matter of my application for Letters Patent for an improvement in sheet-metal packing-cases, filed Sept. 20, 1905, S. No. 279,263. 80

Having thus described my invention, although without having attempted to set forth all the forms in which it may be made or all the modes of its use, I declare that what I claim and desire to secure by Letters Patent, is,— 85

1. A sheet-metal packing-case, consisting of suitable sides and ends suitably secured at the corners of the case, a series of outwardly-extending ribs or flanges formed therewith, a beading formed at the upper and lower edges thereof and inclosing a wire, a bottom suitably secured to said sides and ends and provided with a series of ribs or flanges and openings intermediate said ribs or flanges, a lid or cover provided at its rear with hinge-straps which take over the wire secured within the top beading of the case, supporting-plates mounted and interposed between said 90 sides and ends, an upwardly-extending flange formed about said supporting-plates and secured to said sides and ends, a series of openings formed within said supporting-plates, and annular downwardly-extending flanges formed about said series of openings. 95

2. In a sheet-metal packing-case, the combination with suitable sides and ends bent to form flanged joints at the corners of the case, and a beading formed at the upper and lower edges thereof and inclosing a wire; of a lid or cover, secured at its rear by means of hinge-straps which take over the wire secured within the top beading of the case, a beading formed about the edges of said lid or cover and inclosing a wire, and means for securely holding and locking said lid or cover within and between the top beading of said sides and ends of the case when the same is closed. 100

3. In a sheet-metal packing-case, the combination with sides and ends suitably secured at the corners of the case, a bottom suitably secured thereto, a series of substantially U-shaped outwardly-extending ribs or flanges formed therein, and a beading formed at the upper and lower edges thereof and inclosing a wire; of a lid or cover, secured at its rear by means of hinge-straps which take over the wire secured within the top beading of the case, a beading formed about the edges of said lid or cover and inclosing a wire, a series of ribs or flanges formed in said lid or cover, and means for securely holding and locking said lid or cover within and between the top beading of said ends and sides of the case when the same is closed. 115

4. In a sheet-metal packing-case, the combination with sides and ends suitably secured at the corners of the case, a series of substantially U-shaped outwardly-extending ribs or flanges formed therein, and a beading formed at the upper and lower edges thereof and inclosing a wire; of a bottom secured to the said sides and ends by having its edges bent over and about the said beading, formed at the lower edges thereof, to form a second beading about said lower edges of the case. 120

5. In a sheet-metal packing-case, a wall formed of a single blank of sheet-metal having a series of recesses cut along its margin, opposite where the ribs or flanges are to be formed, and then crimped into a series of U-shaped ribs or flanges, and a beading formed by the marginal edges thereof and abutting against the ends of said ribs or flanges. 125

6. A sheet-metal packing-case consisting of sides, ends 140

and bottom having the edges thereof bent over and about a wire to form a beading, and a series of oppositely-disposed ribs or flanges formed in said sides and bottom and carried up to or abutting against said beading for the purpose of **5** bracing and strengthening said beading.

7. In a sheet-metal packing-case, the combination with sides and ends having the edges thereof bent over and about a wire to form a beading, and outwardly-extending ribs or flanges formed in said sides and ends; of a bottom **10** secured to said sides and ends by having its edges bent over and about said beading, and ribs or flanges formed in said bottom in alignment with the ribs or flanges of said sides.

8. In a sheet-metal packing-case, the combination with **15** sides provided with a beading at the base, and a series of ribs or flanges formed therein and carried up to or abutting against said beading at the base; of a bottom secured thereto and provided with a series of ribs or flanges abutting against said beading at the base and formed in alignment with said ribs or flanges at the sides.

9. A sheet-metal packing-case, consisting of suitable sides and ends each formed of a single blank of sheet-metal having a series of recesses cut along its margin, opposite where the ribs or flanges are to be formed, and then formed **20** into a series of U-shaped outwardly-extending ribs or

flanges, with a beading at the upper and lower edges thereof resting against the ends of said ribs or flanges.

10. A sheet-metal packing-case, consisting of suitable sides and ends, each formed of a single blank of sheet-metal having a series of recesses cut along its margin, a **30** series of U-shaped ribs or flanges formed therein opposite said series of recesses, and a beading formed by the upper and lower edges thereof and abutting against the ends of said ribs or flanges.

11. In a sheet-metal packing-case, the combination with **35** suitable sides and ends suitably secured at the corners of the case; and a beading formed by the upper edges thereof and inclosing a wire; of a lid or cover secured at its rear by means of hinge-straps which take over the wire inclosed by said beading, a beading inclosing a wire formed about **40** the edges of said lid or cover, and adapted to shut down inside and in the same plane with the beading formed by the upper edges of said sides and ends of the case whereby a second strengthening-beading is formed within adjacent to and supporting said first mentioned beading.

In testimony whereof I have affixed my signature in presence of two witnesses.

ALFRED T. KRUSE.
